UNITED STATES PATENT OFFICE.

OLIVE GRACE HENDERSON, OF DETROIT, MICHIGAN.

DESK AND CHAIR.

1,423,661.

Specification of Letters Patent. Patented July 25, 1922.

Application filed December 1, 1921. Serial No. 519,185.

To all whom it may concern:

Be it known that I, OLIVE GRACE HENDERSON, a citizen of the United States, residing at Detroit, in the county of Wayne and State 5 of Michigan, have invented certain new and useful Improvements in Desks and Chairs, of which the following is a full, clear, and exact specification.

This invention relates to desks and chairs 10 especially designed for use in school rooms, and has for one of its objects to provide a chair or seat adapted to be interchangeably used by students of different sizes.

Another object is to provide a combination 15 desk and chair of simplified and improved construction which is durably built and conveniently arranged for use. Other objects will appear as the description proceeds.

The invention will be first hereinafter 20 described in connection with the accompanying drawings, which constitute part of this specification, and then more specifically defined in the claims at the end of the description.

25 In the accompanying drawings, wherein similar reference characters are used to designate corresponding parts throughout the several views:

Figure 1 is a perspective view of a combination desk and chair constructed substantially in accordance with this invention.

Figure 2 is a right hand side elevation of the device.

Figure 3 is a front elevation thereof.

Figure 4 is a left hand side elevation of said desk and chair, and

Figure 5 is a detailed section through the shelf of the chair taken centrally thereof from front to back, showing means for limiting the forward and rearward movements 40 of the foot-stool.

The chair has a seat 1 supported on suitable legs 3 and 4, the two rear ones of which extend above the seat and carry the back 2. 45 Strips 21 may extend between the legs under the seat. The right hand front leg 4 also extends above the seat 1 for supporting an arm 14, the rear end of which is connected to the upward extension of the right hand 50 rear leg 3. The upward extension of the leg 4 also serves to support the right hand rear corner of a desk top 10, the front corners of which are mounted on uprights or legs 11. A strip or apron 12 is preferably 55 fitted between said uprights 11 just below the table top, and the lower ends of said up-

rights, as well as the lower end of the leg 4, are secured to a metal brace resting flat upon the floor. Said brace is substantially L-shaped and may consist of arms 15 and 16 60 extending at right angles to each other and connected by a cross bar 20 as shown in Fig. 1, or any other suitable form of brace for holding the lower ends of the uprights 11 and legs 4 in proper relative position may 65 be employed.

The left hand rear corner of the desk top 10 is supported by a bracket 13 secured to the left hand upright 11, a separate upright support for said corner being omitted in 70 order to permit ready access to the chair from the right hand side thereof. A box or compartment 17 may be secured along the right hand side of the desk for storing writing materials, artists' supplies, or the like. 75 A cover 18 may be hinged at 19 to the upper edge of said box so that when it is folded down it will form a continuation or extension of the desk top 10. Said cover 18 is preferably hinged to the outer edge of the 80 box so that when it is raised or swung upwardly it will not interfere with access being had to the box by the occupant of the chair. Rubber tips 22 are preferably inserted on the top edge of the box 17 where the cover 18 strikes so as to eliminate the noise when said cover is dropped.

85 The chair is provided with a shelf 5 arranged below the seat 1 and preferably supported by two cross spindles 23 between the 90 legs 3 and 4. This shelf may be used for holding students' books and book bags which are usually carried from one class room to another. To the under face of said shelf 5 channeled strips 7 are secured to extend along 95 its lateral edges and face inwardly or toward each other. A foot-stool 6 is fitted to slide in said channeled strips 7 and has its front edge supported on legs 8 suitably secured to the under surface thereof by metal angle 100 braces 9, as shown in Figures 2, 3 and 4. Said foot-stool may be projected beyond the front edge of the shelf 5 as illustrated in Fig. 1, and in dotted lines in Fig. 2, when the chair is used by a small child. When a 105 larger student occupies the chair, the foot-stool 6 is pushed back in the guiding channels 7 to a position below the shelf 5 where it is entirely out of the way, as indicated in solid lines in Fig. 2, and also in Fig. 4. The 110 outward and inward movements of the foot-stool may be limited in any suitable man-

ner, as by metal stops 24 and 25 screwed under the shelf 5, and adapted to contact with a plate 27 secured to the rear edge of the foot-stool and projecting above the 5 same, see Figure 5.

The provision of the sliding foot-stool makes it possible for a uniform size of chair to be used throughout a number of class rooms in which students of different ages 10 or sizes are to be accommodated. The chair equipped with said sliding foot-stool may also be employed to advantage in the class rooms of high schools or other educational institutions where the same room is occupied 15 during the day by different classes made up of students of various ages and sizes. Thus the same size of desk and chair constructed in accordance with the present invention may be used to accommodate all grades from the 20 first to the eighth, as well as high-school classes.

The provision of the braces between the desk supports or uprights and the chair leg insures steadiness and firmness of the desk 25 and chair, so that there is no danger of paint pans or paint boxes sliding off while in use and spilling water and paint on the floor or clothing of the user. The arrangement of the storage compartment at one side 30 and on a level with the desk top makes it easy for students to take out and put away supplies quickly and noiselessly. It will also be noted that the rigid connections between the desk and chair make it possible for them 35 to be moved from place to place as a single piece of furniture without disturbing the proper relative positions of one with respect

to the other. Moreover, the desk top being level, ink and other supplies may be placed thereon without danger of upsetting, and 40 the desk is constructed so that no bolt heads or ragged edges of iron come in contact with the hands or clothing of the occupant.

The legs 3 of the chair and supports 8 of the foot-stool may have metal knobs or 45 silence domes 26 attached thereto so as to slide freely over the floor.

I claim:

1. The combination with a chair, of a desk arranged in front of the same, one of 50 the front legs of the chair being extended upwardly to support one of the adjacent corners of the desk, supporting means reaching to the floor from both of the remote corners of the desk, and a substantially L- 55 shaped brace to extend along the floor and connect the bottom of said supporting means with the lower end of the leg having said upward extension.

2. The combination with a chair, of a desk 60 arranged in front of the same, an arm at one side of the chair extending to the corresponding side of the desk, a storage compartment extending along one lateral edge of the desk beyond said arm, and a removable cover for said compartment adapted when closed to abut against said lateral edge of the desk and lie in the same plane with 65 said desk so as to constitute a continuation thereof.

In testimony whereof I have signed my name to this specification.

OLIVE GRACE HENDERSON.
